PIVOTED CUTTER FOR DISPENSING CONTAINERS

Price G. Turner, Yorkville, N. Y.

Application February 18, 1946, Serial No. 648,479

2 Claims. (Cl. 164—43)

1

My invention relates to a dispensing container for adhesive tape, and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a container for holding a spool of adhesive tape or plaster usually kept in the home for emergency first aid cases. The container allows the plaster to be dispensed in predetermined lengths as desired. It will be found useful also for holding and dispensing adhesive tape used in place of string for tying packages.

The container is designed to hold the plaster or tape in such manner that its free end will be readily available to the user, whereby he can grasp said free end and after pulling the tape to the desired length with the fingers of one hand, use the fingers of the other to close the knife carrying member for severing the tape.

The container is provided with a removable cover which allows for an easy and simple means of reloading the container with a new roll or spool of tape or plaster.

The object will be understood by referring to the drawings in which:

Fig. 1 is a perspective view of the container, parts being broken away.

Fig. 2 is a side elevation, showing the cover removed.

Fig. 3 is an end elevation, showing parts broken away.

Fig. 4 is a detail view, showing a perspective of a channel member employed in the device.

Fig. 5 is a detail view showing a side elevation of a knife carrying member employed in the device.

Fig. 6 is a detail view showing a perspective of a cover employed, parts being broken away.

Referring more particularly to the drawings, the device embodies an annular casing 1 having an embossed ridge 2 disposed near the free edge 3 of lateral wall 4, whereby to form a stop for the adjacent edge of removable cover 5 against which it abuts when said cover 5 is in closed position.

There is welded or otherwise mounted to casing 1 on wall 4, a channel member 10 having lateral sides 11, 11. A stationary shaft 12 is suspended between said walls 11, 11 near one end thereof. The ends of said shaft are riveted to said sides or walls 11, 11. Shaft 12 provides an axle for knife holding member 14 to swing thereon as a

2

pivot. To this purpose one end of member 14 is bent around shaft 12 to form a bearing surface for member 14.

A member 15 is welded to the free end of member 14. It has formed integral therewith and at right angles thereto knife blade 16 which tapers from one end to the other crosswise as shown particularly in Fig. 1. The surface of blade 16 from top to bottom thereof is made on the arc of a circle whose imaginary center is the axial center of shaft 12, whereby to form a co-operating surface with knife blade 17 hereinafter mentioned.

Knife blade 17 is welded to the opposite ends of sides 11, 11 of channel member 10. The flanged part 17' thereof is welded to the lower surface 18 of channel member 10. It tapers crosswise from one end to the other similar to the taper of knife blade 16, whereby to form a pair of scissors therewith. Furthermore, blade 17 is made on the arc of a circle whose imaginary center is the axial center of shaft 12.

The means for holding the spool of tape 19 within casing 1, contemplates a cylindrical member 20 welded to the inner surface of casing 1 and outstanding therefrom. Said member 20 is disposed eccentric to the surface of casing 1, whereby to allow more space above than below in chamber 21 of casing 1. This additional space above member 20 in chamber 21 will prevent the peripheral surface of the spool of tape 19 from binding against the inner surface of wall 4 of casing 1 in the event that the central aperture of the spool of tape 19 is larger than the diameter of member 20. This binding would occur when the user pulls on the free end 22 of tape 19 to withdraw a portion thereof.

The means for holding the free end 22 of tape 19 embodies a flat spring 25 whose lower end is welded to the inner wall of casing 1 at 26. A loop 27 is made in spring 25 to provide a smooth surface for the passage of tape 19. It is extended upward through an aperture 28 in wall 4 of casing 1 and through an aligned aperture 29 in the lower surface 18 of channel member 10 with its free end 31 raised a little above the upper edges of sides 11, 11 of member 10, whereby to hold the free end 22 of tape 19 in convenient position for grasping with the fingers.

A narrow slit 35 is made in one of the sides 11 of member 10 to allow for the easy insertion of tape 19 into correct position with its free end 22 resting on spring 25, adjacent end 31 thereof.

Cover 5 has an aperture or reentrant hole made in its lateral wall 37 to cooperate with the aligned

apertures 28 in wall 4 and 29 in channel member 10, when in closed position.

A narrow space 40 is provided between that portion of the under surface of channel member 10 from ridge 2 to the outer marginal edge of wall 4, whereby to allow for the insertion of that portion of wall 37 of cover 5 when in closed position.

In operation, the user will remove cover 5, insert a roll of adhesive tape 19 on member 20, thread the free end 22 thereof edgewise through slit 35 into aligned apertures 28 and 29 with its free end 22 resting on the free portion 31 of spring 25. When it is desired to use a portion of tape 19, the operator will lift the free end of member 14 and swing it upward, then grasp with the fingers of one hand the free end 22 of tape 19 and after drawing out a predetermined length, use the fingers of his other hand to close member 14, whereby knives 16 and 17 will shear tape 19, leaving the free end 22 of said tape 19 clinging to the upper surface of the free end 31 of spring 25.

The rounded ends 41, 41 of sides 11, 11 will serve as a guide for knife blade 16 when it is lowered relative to knife blade 17 to effect a shearing contact therewith, similar to the action of a pair of shears.

Having thus described my invention what I claim as new and desire to secure by Letters Patent is as follows:

1. In a dispensing container for adhesive tape, a casing, a channel member mounted on said casing, a stationary knife tapering from one end to the other mounted in said channel member, a pivotally mounted knife tapering from one end to the other, mounted in said channel member, whereby to cooperate with said stationary knife to shear said tape, said channel member having rounded ends for guiding said pivotally mounted knife relative to said stationary knife, and a spring mounted in said channel member for

holding the end of said tape in predetermined position.

2. In a dispensing container for adhesive tape, an annular casing, a channel member having sides mounted on said casing, a stationary knife tapering from one end to the other mounted in said channel member, a knife holding member pivotally mounted in said channel member, another knife tapered from one end to the other carried by said holding member, whereby to cooperate with said stationary knife, to shear said tape, a slit formed in one of these sides of said channel member to allow for insertion of tape relative to said knives, the sides of said channel member having rounded ends for guiding the knife carried by the holding member, relative to the knife in the channel member, and a spring mounted in said channel member for holding the end of said tape in given position.
